WATER HEATING SYSTEM FOR BOTTLE
WASHING MACHINES

Grover C. Evans, Little Rock, Ark.

Application August 29, 1935, Serial No. 38,447

6 Claims. (Cl. 237—8)

This invention relates to improvements in water heating apparatus and pertains particularly to and improved apparatus for heating and automatically controlling bottle washing machines.

In industrial enterprises where it is necessary to use water heated to different temperatures, such, for example, as in bottling establishments where tanks of heated water known as soakers are employed, it is the usual practice to supply the heated water from heaters which are placed at a lower elevation than the tanks or soakers, either by placing the water heaters in a room below the tanks or by constructing pits in which the heaters are placed, or by placing burners directly beneath the soakers or water tanks. In the first method, the circulation of the water through the tanks depends on convection and it is, therefore, always necessary to have the heaters below the tanks so that the cooler water will return by gravity thereto. This type of heating installation is expensive and the use of burners directly beneath the water tanks or soakers is unsatisfactory because of the difficulty of regulating the temperatures for several soakers.

The present invention has for its primary object to overcome the undesirable features associated with the methods above described by the provision of mechanism which may be placed below, at the same elevation as or above the soakers with the production of satisfactory results in that water or other fluid used in the soakers or other tanks being supplied may be continuously circulated and may be maintained automatically at an even temperature.

Another object of the invention is to provide in a water heating system a novel means of supplying a series of tanks or other receptacles with heated fluid and maintaining different temperatures in the several tanks.

Still another object of the invention is to provide in a water heating system a novel means of maintaining a heating coil filled with the fluid of the system while the system is idle, when the heaters and the liquid receiving tanks are placed at substantially the same elevation.

A further object of the invention is to provide in a water heating system a novel arrangement and combination of units of standard design by which the foregoing described desired results are obtained.

The invention will be best understood from a consideration of the following detailed description taken in connection with the accompanying drawings forming part of this specification, with the understanding, however, that the invention

is not confined to any strict conformity with the showing of the drawings but may be changed or modified so long as such changes or modifications mark no material departure from the salient features of the invention as expressed in the appended claims.

In the drawings:

Figure 1 represents a diagrammatic lay-out of the apparatus embodying the present invention, viewing the same in top plan;

Figure 2 represents diagrammatically an end elevational view of the apparatus showing a central one of the tanks in section;

Figure 3 is a diagram of the electric circuit in which the aquastats and electrically operated gas valve are connected.

Referring to the drawings wherein like numerals of reference designate corresponding parts throughout the several views, the numerals 1 to 4 inclusive indicate fluid receptacles which are illustrated in the form of tanks and which may represent soakers of the type used in beverage bottling plants. The numeral 5 indicates generally a battery of gas fired heaters of the type commonly employing a water circulating coil (not shown), each of the heaters being indicated by the numeral 6. These heaters are shown mounted upon a supporting stand 7 whereby the lower ends of the coils thereof and the burners 8 are disposed at an elevation above the bottoms of the tanks.

Extending along the lower part of the battery of heaters is a manifold 9 and above the heaters and extending longitudinally of the battery is a second or upper manifold 10. The lower manifold 9 is connected by lead-off pipes 11 with the lower ends of the coils of the adjacent heaters while the upper manifold is connected with the upper ends of the heater coils by the lead-off pipes 12.

Gas fuel is supplied to the burners of the heaters from the main 13 to the distributing pipe 14 from which its passage to the several burners is controlled by manual valves 15. A suitable shut-off valve 16 is located in the main and the gas fuel after passing through this valve passes through a pressure regulator 17 and through a suitable standard type of electrically controlled gas valve which is conventionally illustrated and indicated by the numeral 18. This valve 18 may be of any standard make such, for example, as the type F motor gas valve of the Minneapolis Honeywell Regulator Company. Thermostatic means electrically connected with this gas valve effects the opening and closing of the same in

the manner hereinafter more particularly described, in accordance with the needs of the tanks, to light up or shut off the burners of the heaters.

5 The pipe line 19 constitutes a manifold for supplying pilot lights in the heaters through the several short lead-off pipes 20 connected therewith.

At the central part of the top manifold 10, a 10 T-coupling 21 is connected which couples a pipe line 22 between the manifold 10 and the distributing pipe 23 for the tanks 1 to 4 inclusive. This distributing pipe 23 has a valved connection 24 with the tank 2 so that fluid may be discharged directly into the tank 2 from the pipe 23 and the tanks 1 and 3 contain coils 25 and 26, respectively, which are coupled with the distributing pipe 23, respectively, through the medium of the valves 27 and 28. The tank 4 also contains a coil which is indicated by the numeral 29 and which is connected with the pipe 23 to receive liquid therefrom through the control valve 29'. This valve and the valves 27 and 28 normally remain partially closed to control the amount of liquid flowing through the coils. The temperature of the liquid in the tanks 1, 3 and 4 is kept below that in the tank 2; therefore, by regulating the valves 27, 28 and 29', the liquid flow through the coils can be cut down so as to keep the liquid in the tanks at the desired temperature.

30 A receiving manifold for the liquid passing through the tank 24 and the coils 25, 26 and 29 is indicated by the numeral 30 into which each of the coils discharges, as shown, and which has a discharge pipe leading therefrom, as indicated at 31, into the tank 2.

An outlet pipe 32 having a control valve 33 leads from the tank 2 through a strainer 34 and a second valve 35 into a pump 36 of the centrifugal 40 type preferably, which is propelled by an electric motor 37. The outlet side of the pump 36 has one end of a pipe 38 connected therewith and this pipe extends upwardly from the pump to the top of the heater unit or battery where it is joined 45 by a coupling 39 when a vertical downwardly extending pipe 40 which at its lower end is coupled with and leads into the bottom manifold 9.

Extending across and forming a shunt between the upper end of the pipe 40 and the pipe line 22, 50 is a small diameter pipe 41 and connected with this pipe is an inwardly opening check valve 42, the purpose for which will be hereinafter more fully described. Since the upper end of the pipe 38 is directed inwardly toward and is in the 55 same plane as the connection by which the pipe 22 is coupled with the manifold 10, the preferred practice would be to join these together so as to form a rigid structure, in which case the joining pipe would be plugged off, as indicated at 43 in 60 Figure 2. However, in the present illustration, these parts are shown free of connection one with the other so that the relation of the pipes may be more clearly set forth.

The numerals 44 and 45 each indicate an electric circuit controlling instrument of the thermostat variety, the preferred type of instrument being that known as an immersion aquastat of the variety produced by the Minneapolis Honeywell Regulator Company, although any type of 70 thermostat suitable for the purpose may be employed. The thermostat 44 is set to operate at a higher temperature than the thermostat 45, and as illustrated, the thermostat 44 is inserted in the pipe line coupling the outlet manifold 10 75 with the tanks whereas the thermostat 45 which

operates at a lower temperature extends into the tank 2 so as to be actuated by the temperature of the water or other liquid therein.

In the operation of the present apparatus, the heat responsive device or aquastats 44 and 45 are 5 electrically connected with the electric gas valve 18 and the motor 37, as illustrated in the circuit diagram constituting Figure 3 of the drawings and the aquastat 45 normally controls the operation of the motor and pump unit and the gas 10 valve 18. When the pump 36 is operating, the water or solution will be withdrawn from the tank 2 through the screen 34 where any undesired particles will be strained out and is then passed upwardly through the pipe 38 and back 15 down to the pipe 40 to the intake manifold 9. The solution then passes through the heaters and is discharged into the upper manifold 10 to flow past the aquastat 44 to and through the pipe 22 to the distributing pipe 23. Part of the 20 solution then passes directly into the tank 2. By throttling or closing down the valves 27, 28 and 29', enough of the hot solution or water is permitted to pass through the coils to hold the water or solution in the tanks in which these 25 coils are located at a desired temperature. All of the water or solution from the coils is returned by way of the pipe 31 to the tank 2 and as the temperature of the water or solution reaches the desired maximum, the aquastat 45 operates to 30 shut off the current supply to the circulator or pump 36 and to close the valve 18. When the temperature of the solution in the several tanks or soakers drops below the minimum desired, this 35 aquastat will operate to close the electric circuit in which it is located so as to start the circulator or pump and open the gas valve.

The heat responsive element or aquastat 44 is set for high limit control, that is, it is set 40 to operate at 10, 15 or 20° higher than the aquastat 45 in the soaker or tank 2. Should the solution fail to reach the heaters in sufficient 45 quantities while the gas valve is open so that the burners are ignited and while the pump is operating, as in the case of an obstruction in the strainer or circulating lines, or in the event of failure of the pump to operate, this element 44 responds to the increased degree of temperature which would naturally result and shuts off the current supply to the gas valve 18 and also to 50 the motor 37. This element 44 operates merely as a safety device whereas the element 45 operates continuously for maintaining the temperature of the solution or the water in the tanks or soakers at the proper degree of heat.

55 Referring particularly to the circuit diagram illustrated in Figure 3, it will be seen that each of the aquastats has six terminals, the aquastat 45 having its terminals indicated by the numerals 46, 47, 48 and 46', 47' and 48' while the aquastat 44 has its terminals indicated by the numerals 49, 50, 51 and 49', 50' and 51'. The primed terminals of the aquastats designate the lead-off terminals while the others are the lead-in terminals. In each aquastat is a pair of contact arms which in aquastat 45 are indicated by the numerals 52 and 53 while in aquastat 44 they are indicated by the numerals 54 and 55, and these arms are shifted or actuated by a bimetallic element which extends from the aquastat and which is encased in the housing 56 in the aquastat 45 as illustrated in Figure 2. The same construction is used in aquastat 45 but is not illustrated. The arms 52 and 53 coat with the terminals 52' and 53' in opening and clos- 75

ing the circuit which the aquastat controls and the arms 54 and 55 of aquastat 44 coact with the terminals 54' and 55'.

The current supply line is indicated generally by the letter L from which current is taken, preferably through a transformer 57 to the circuit 58, one side of which is coupled with the terminal 47 of aquastat 45 while the other side is coupled with the terminal 46 of the same aquastat and has the field coil 58 of an electric motor therein. The numeral 59 indicates diagrammatically the rotor of a motor which forms a part of the electrically operated valve 18 and the coil 58 comprises the field of this motor. The contact arm 52 of aquastat 45 is electrically coupled through the terminal 46' and the terminal 49 of aquastat 44, with the contact 54' and the arm adjacent this latter contact and which is indicated by the numeral 54, is electrically coupled with the lead-out terminal 49' which in turn is electrically connected through the terminals 51', 51, 48' and 48 with a wire 60 which leads to a contact point 61 forming a part of the mechanism of the valve 18. As illustrated, the longer arm 53 of the aquastat 45 is electrically coupled with the contact point 55' of aquastat 44 with which the arm 55 of this instrument is adapted to engage, and this latter arm is electrically coupled with the center lead-out terminal 50' of this aquastat.

The electrically actuated control valve structure 18 includes a gear 62 which is in geared connection with the rotor or armature 59 of the electric motor which forms a part of this valve structure. This gear 62 is connected with a shaft 63 on the end of which is a cam 64 which is frictionally coupled therewith and which is limited in its oscillatory motion by the pin 65 engaging in the recess in the periphery thereof. The contact arm 66 is shifted upon the movement of the cam 64 into electrical engagement with the point 61 and this arm is electrically coupled by the wire 67 with the motor field coil 58.

The gear 62 carries a pin 68 adapted to engage the hooked end 69 of a link 70 and this link is pivotally attached to an arm 71 which when moved in one direction against the tension of a spring 72 opens the valve controlling the flow of gas through the line 13. The raising of the arm 71 oscillates a mercury switch 73 which closes a circuit in which the electric motor 37 is located so that upon the opening of the valve mechanism, the electric motor 37 will start functioning.

In the operation of the apparatus, when the liquid in the tank 2 drops below the temperature required, the arms 52 and 53 will be moved into contact with the points 52' and 53' and the same action will occur in the aquastat 44 so that electric current will pass through the circuit 58 by way of the terminals 47, 47', 50, 50', 49', 49, 46' and 46, flowing through the field coil 58 of the electric gas valve motor. This starts the motor operating and causes the pin 68 to engage the hook 69 to open the valve in the line 13. When the pin 68 engages the hook 69 and the valve is opened fully, the motor will be stalled but current will continue to flow through the field coil of the motor because of the movement of the arm 66 against the point 61 by the cam 64 which was partly turned with the gear 62. The arms 52-53 and 54-55 of the two aquastats are so adjusted that as the temperature in the apparatus rises, the shorter ones of the arms will separate from their points 52' and 54' in

advance of the longer arms. By this means, the motor 37 will be kept in operation and the gas line 13 will be kept open through the continued energization of the coil 58 after the heat responsive devices have begun to operate. After the temperature in the tank 2 has been raised to the proper point, the aquastat 45 will open fully and the current supply cut off to the coil 58, whereupon the reaction of the spring 52 in closing the gas valve will effect a slight reverse rotation of the gas valve motor which will reversely rotate the cam 64 and move the arm 66 away from the point 61.

With the arrangement of the pipe 38 as shown, the water or solution is carried to the top of the heaters so that the danger of the heaters being ignited while the coils thereof are only partially filled with water or solution is eliminated. This condition might occur if the heaters are located at a high elevation with respect to the tanks so that the natural leveling of the water in the system would result in the lowering of the water level in the heater coils.

The check valve 12 in the pipe line connecting the return and discharge pipes for the heaters operates to break a siphon which may occur and drain the coils to the level of the water in the soakers or tanks particularly if the tanks are placed at a lower level with respect to the heaters, thus leaving the coils empty or partly empty of water or solution when the system is not in operation. In the present illustration, the heaters have been shown at such an elevation with respect to the soakers or tanks that the coils of the heaters might be partially drained by the siphoning action described or by the water finding its natural level if the riser pipe 38 and check valve were not provided. It will be readily apparent that the higher the heaters are placed with respect to the tanks, the greater the water level drop would be in the heaters if the check valve and arrangement of pipe 38 as shown were not employed. If the water level of the tanks or soakers is higher than the tops of the heaters then the siphon breaking check valve need not be employed as the stand of water in the heater coils would always be at the top of the same.

What is claimed is:—

1. In a water heating system, a plurality of heated water receiving units, a heater unit, pipe means for conducting heated water from the heater unit to each of the receiver units, means for returning water from certain of the receiver units into one receiver unit, means for returning water from the said one receiving unit to the heater unit, an electrically operated circulator in said water return means, an electrically operated element controlling the operation of the heater unit, and an electric circuit controlling heat responsive device disposed in said one water receiving unit and connected with said circulator operating means and heater unit controlling means to control the operation of the same in response to temperature variations in the said one receiver unit.

2. In a water heating system including a water heater and a water receiving receptacle disposed on the same elevation, a pipe line leading from the upper part of said water heater to said receptacle, a return flow pipe leading from the receptacle, a water circulator having said return flow pipe leading thereto, a vertically disposed pipe connected at its lower end to the lower part of said heater, the upper end of said vertically disposed

pipe being above the upper part of the heater, a pipe connecting the circulator with the upper end of said vertically disposed pipe, and means permitting the introduction of air into the upper end of the vertically disposed pipe and the first mentioned pipe to prevent a siphon effect when the circulator is idle.

3. A water heating system, comprising a plurality of receptacles, a hot water coil disposed in all but one of said receptacles, a water distributing pipe connected with each of said coils and with the said one of said receptacles for the discharge of water into each of the coils and the said one receptacle, a return water collecting pipe connected with each of said coils to receive water therefrom and having a discharge pipe opening into the said one of the receptacles, a heater unit, a return flow pipe line leading from the said one of the receptacles to the heater unit, a water circulator in the return flow line, a hot water line leading from the heater unit to said distributing pipe, electric means operating said circulator, and an electric circuit controlling heat responsive element in the said one of the receptacles which is electrically connected with the circulator operating means to start or stop the same in accordance with the water temperature in the receptacle in which the heat responsive element is located.

4. In a system of the character set forth, a liquid receptacle, a liquid heater, electrically operated means controlling the operation of said heater, a liquid pipe line leading from the receptacle to said heater, a liquid pipe line leading from the heater to the receptacle, electrically operated circulating means in one of said pipe lines, an electric circuit controlling thermostat connected with the receptacle and controlling the flow of electric current to said electrically operated heater controlling means and circulating means whereby both of said means will be placed in operation at a desired low temperature in

the receptacle and cut out of operation at a desired high temperature, and a second electric circuit controlling thermostat in series with said first thermostat and located in one of said pipe lines to effect the cutting out of operation of both of said means at a predetermined high temperature in the line in the event of failure of the heated liquid to reach the receptacle.

5. In a system of the character described, a pair of liquid containers, a liquid heater, a pipe line leading from said heater to said containers and discharging directly into one of the same, a pipe connected at one end with said line and passing through the other container and discharging at its other end into the said one container, a pipe leading from the said one container back to said heater, a circulator in one of said lines, an electric motor operating said circulator, and a heat responsive electric circuit controlling device in the said one container and controlling the operation of said motor.

6. In a system of the character described, a plurality of containers, one constituting a master container, a liquid heating means, a liquid supply manifold adjacent said containers, a liquid receiving manifold, a pipe leading from said heating means to the supply manifold, a coil in each of the containers excepting the master and having an end connected with the supply manifold, pipe means connecting the supply manifold with the master container for discharge directly thereto, each of said coils having its other end connected with the receiving manifold, said receiving manifold having a discharge outlet into the master container, a pipe leading back from the master container to the heating means, electrically actuated circulating means in one of said pipes, and an electric circuit controlling heat responsive device in said master container controlling the operation of said circulating means and of said heating means.
